UNITED STATES PATENT OFFICE.

JOHN L. GIDEON, OF OMAHA, NEBRASKA.

PAPER-RECEIVING TABLE.

1,188,064.

Specification of Letters Patent. Patented June 20, 1916.

Application filed May 17, 1913. Serial No. 768,340.

To all whom it may concern:

Be it known that I, JOHN L. GIDEON, a citizen of the United States, and a resident of Omaha, in the county of Douglas and State of Nebraska, have invented certain new and useful Improvements in Paper-Receiving Tables, of which the following is a specification.

My invention relates to receiving tables for use with automatic sheet-delivering devices on printing presses.

It is the object of my invention to provide a simple, inexpensive and convenient paper-receiving table, especially adapted for use in connection with my paper-feeding attachments for Gordon presses, for which I have made application for Letters Patent, filed Feb. 21, 1913, Serial No. 750,011.

In the accompanying drawings, Figure 1 is a side view of mechanism embodying my invention, together with the associated parts of the press and of the sheet-severing and delivering mechanism, Fig. 2 is a front view of the receiving-table and actuating mechanism therefor, and Fig. 3 is a plan view of the table-actuating mechanism.

In Fig. 1 there is shown a portion of the main frame 1 of a press, the same having mounted on the upper part thereof the frame 2 of the paper-feeding and sheet-delivering mechanism. The said mechanism delivers the sheets at a point between the sides of the frame 2 near the front part thereof, as described in the above mentioned application.

The receiving-table and its actuating mechanism is supported on a pair of rods 3 which are secured to and extend downwardly from the frame 2. At the lower ends of the rods 3 a cross-frame 4 is secured to them and connects them to each other. At the center of the cross-frame is a hub 5 having a vertical cylindrical opening through it. A ratchet-wheel 6 has an elongated cylindrical hub or sleeve 7 which extends through the hub 5, fitting revolvably therein. The sleeve has a shoulder thereon near the upper part thereof which rests on the upper side of the cross-frame 4 so as to hold the ratchet-wheel slightly above the same. A collar 8 is secured to the sleeve below the hub to prevent the sleeve being withdrawn therefrom. A threaded rod 9 passes slidably through the ratchet-wheel and the sleeve 7, and supports at its upper end the table 10.

At the ends of the table are secured the guide-members 11 which extend out laterally and slidably engage the rods 3. The threads on the rod 9 are of the kind known as "butress" or "ratchet" threads, being formed with the lower sides perpendicular to the axis of the rod, like a square thread, and with the upper sides beveled or inclined like a V-thread. A divided nut 12 is connected with the ratchet-wheel and engages the threaded rod above the wheel. Each part of the nut is pivotally connected with the wheel by means of an arm 13, and the parts are yieldably held together by springs 14 of which the ends are connected to lugs on the sides of the parts, as shown in Fig. 3.

For actuating the ratchet-wheel there is a pawl-lever 15 which is pivoted on the part of the sleeve 7 above the frame 4 and beneath the ratchet-wheel. On said lever is carried a pawl 16 which is yieldingly held in engagement with the wheel by a spring 17. A curved lever 18 is pivoted on the frame 4 near one end thereof, and one end of the said lever is pivotally connected with a rod 19 which extends to and is similarly connected to the outer end of the pawl-lever. The other end of the lever 18 is connected by means of a rod 20 with a reciprocating part of the press, such as the bed, so as to cause a reciprocating movement of the said lever 18 and the pawl-lever, such movements being synchronous with the movements of the press and the sheet-delivering mechanism. At each movement of the pawl-lever 90 the ratchet-wheel is advanced one tooth and, the nut 12 being similarly turned, the threaded rod is slightly lowered. The parts are so proportioned that the lowering of the rod and receiving-table at each movement 95 of the ratchet-wheel is approximately equivalent to the thickness of one of the sheets of paper delivered to the table. Thus as the sheets accumulate on the table the top 100 of the pile A is maintained at a substantially uniform level. After the mechanism has been in operation for such a time that the table has been lowered to a point near the lower limit of its movement, the pile of sheets A may be removed from the table and 105 the same raised to its first position. To raise the table it is merely necessary to pull it upwardly, upon which the beveled or inclined upper sides of the ratchet-threads on the rod 9 will spread apart the members of the 110

divided nut 12 so that the rod can pass through it. When the table is raised sufficiently the springs 14 close the nut onto the rod again, and the intermittent lowering of the table may proceed as before described.

Now, having described my invention, what I claim and desire to secure by Letters Patent is:

1. A sheet-receiving attachment for printing presses comprising a cross frame, separated parallel rods each fixed at one end to the cross frame and adapted to be connected to a portion of the frame of the machine at the other end to hold the cross frame suspended, a sheet-receiving table having members engaging with said rods for guiding the table, a screw shaft connected to the underside of the table and extending down through said cross frame, and means including a screw threaded member supported by said cross frame for coöperat-

ing with said screw threaded rod to raise and lower the same.

2. A sheet-receiving attachment for printing presses comprising two parallel rods 25 adapted to be connected at their upper ends to the frame of a printing press, a cross frame rigidly connected to the lower ends of the rods, a sheet-receiving table slidable up and down upon the rods, a screw extending downwardly from the under side of the table through said cross frame, and means carried by the cross frame and including a nut coöperating with said screw for raising and lowering the screw and the table. 30 35

In testimony whereof I have hereunto subscribed my name in the presence of two witnesses.

JOHN L. GIDEON.
